MEANS AND METHOD OF CLOSING
SURGICAL INCISIONS

Carl E. Conn, Los Angeles, Calif.

Application June 8, 1936, Serial No. 84,120

3 Claims. (Cl. 128—335)

This invention relates to suturation devices and methods of their use by which the sides of incisions may be supported in closed relation for prompt and effective cicatrization and effective healing thereof upon completion of a surgical operation.

At the conclusion of an abdominal operation, for instance, the walls of the incision are usually supported adjacent one another to permit the wound to heal by sutures of various well known types. Sutures of the prior art which do not allow for subsequent swelling of the tissues tend to cut and irritate the wound. The necessary time for healing is thus prolonged, during which the discomfort of the patient is increased and the resultant scar is often excessively large or deep, and occasionally completely opened, permitting extrusion of abdominal contents following excessive straining from vomiting or coughing.

It is also important that access to the incision be unrestricted to aid inspection and bathing of the wound; and that replacement of the dressing be facilitated, without disturbance of the sutures or of the healing process.

It is an important object of the present invention to provide a suturation device for resiliently supporting in closed position all or any portion of an incision and thereby prevent cutting of, or undue strain or constriction upon the tissues through which the suture passes.

Another object is to provide a wound closing suture assembly adapted to be suspended from skin surfaces adjacent the incision to resiliently maintain the walls thereof together, which enables free access to the wound for subsequent treatment and cleansing, and further presents a flat surface of small bulk to minimize the risk of displacement or strain by bedding or clothing.

Another object is to provide a cushion to support suspension means for a suture, composed of resilient material which may be impregnated with antiseptics and adapted to absorb secretions which tend to flow from the depths of the wound along the suture to the skin surface.

Another object is the provision of a suture cradle to hold opposite walls of an incision together, which may be adapted to completely encircle the wound without construction of the deeper tissues by the addition of removable rubber bands or suture material tied across connecting the top of the cradle, said bands being useful in maintaining position of a surgical dressing on the surface of the wound.

Another object is the provision of a method

for the most effective and efficient utilization of a device embodying the characteristics of the above-noted objects, which results in greater comfort to the patient, smaller scars, and speed in healing.

Other objects and advantages will be apparent to those of skill in this art upon an examination of the following description read in the light of the accompanying drawing, in which—

Fig. 1 is a perspective view of a suture button 10 of my invention;

Fig. 2 is a perspective view of the cushion hereof;

Fig. 3 is a somewhat diagrammatic view illustrative of the incised abdominal wall and overlying layers of muscular tissue and fat with my invention operatively applied thereto;

Fig. 4 is a plan view of the invention as shown in Fig. 3;

Referring to the drawing in detail, the numerals of which indicate similar parts throughout the several views, 5 and 6 designate, respectively, the outer layer of fat and an under layer of muscular tissue of a patient, separated and bound together by fascia 7, which covers the abdominal wall 8. An incision of a surgical operation through the layers 5 and 6 and wall 8 is indicated at 9.

A suture button 10 is provided comprising a flat disk having diametrically-disposed slots 11 at opposite sides of its center. A central bar 12 separates the inner ends of said slots 11. Upon completion of the surgical operation, a silk suture 13, doubled in a curved needle (not shown), is hooked over the bar 12 of the disk and is threaded through the center of a circular sponge rubber cushion 14. The needle is then passed through the skin 15 of the patient at one side of the incision, carrying the suture 13 downwardly through the outer layers 5 and 6, curving toward the incision at any depth desired, and then is returned to the surface at the opposite side of the wound. The sides of the incision are then drawn together, the tissue being sutured as indicated at 16.

The free end of the silk suture 13 is passed through another sponge rubber cushion 17, and after applying suitable tension, its end is securely tied to the bar 18 of a second disk 19 which is adapted to rest on cushion 17 to support the incision in a U-shaped cradle thus suspended resiliently on the skin of the patient.

The plane in which the suture 13 is disposed is preferably at right angles to the incision to maintain alignment of opposite sides thereof,

and to cooperate with the sutures 16 in supporting adjacent tissue while the wound is healing.

It will be obvious to those of skill in the art that the degree and direction of support of sutures 13 may be varied by altering the spaced relation with the incision of opposite reaches of the thread. A series of such cradles may be employed in the same manner, the number being influenced by the nature, location, length, or 10 depth of the incision.

A surgical dressing 20 covering the wound between the disks may be firmly yet resiliently maintained in position by rubber or inelastic bands 21, each of which is hooked at opposite 15 sides to the silken suture at a point between the cushion 14 and disk 10 and cushion 17 and disk 19. The bands 21 may be removed at will without disturbing the cradle, thus enabling cleansing 20 or treatment of the incision and replacement of the dressing.

As above noted, the cushion 17 on which the discs 19 are supported is composed of sponge rubber of a size and a sufficiently absorbent quality to absorb secretions which tend to flow from 25 the depth of the wound through the passages formed by the needle, through which the sutures extend, to the skin surface. The cushions may be impregnated with any suitable medicaments or antiseptics which, upon compression of the cushions 30 by the buttons incident to the swelling of the wound after the operation, will expel the medicament into the passages through which the sutures extend to treat the depths of the incision.

It will thus be seen that I have provided a suture adaptable to support in a U-shaped cradle incisions of any length or depth, carrying cushioning means to permit expansion of the tissues by swelling or flexing of the wound during movement of the patient, thereby preventing excessive tension of the silk thread which might result in cutting of the flesh by either the thread 40

or disk. The disks further provide a flat surface, free of projections with which clothing of the patient or bedding may become entangled to tear or break the wound or displace the sutures or dressing.

It will be obvious that numerous changes may be made in the embodiment shown, particularly in the form of disk; that any well known suture material may be substituted for the silk thread described; that the number or particular spaced arrangement of the composite cradles may be varied to meet specific requirements, and that while the invention is described as applied to an abdominal incision, it will be apparent that the device is applicable to wounds of any similar 15 nature at any part of the body—all without departing from the spirit of my invention.

What I claim and desire to secure by Letters Patent is:

1. The method of closing surgical incisions comprising attaching one end of a suture to a supporting button, passing the opposite end of the suture through a resilient cushion, passing the suture downwardly through the skin of the patient, at one side of the wound, thence through 25 the incision and through the skin at the opposite side of the incision, passing the suture through a cushion and securing its end to a supporting button.

2. The method of supporting the ends of a U-shaped suture having its ends emerging from the skin of a patient at opposite sides of an incision consisting in passing the ends of the suture through cushions and securing the ends of the 35 suture to buttons.

3. In a wound closing device, a suture adapted to extend through an incision and protrude from the skin of a patient at opposite sides of the incision, buttons for attachment at each end of the suture, and a cushion for the support of each 40 button.

CARL E. CONN.
